UNITED STATES PATENT OFFICE.

FRANK F. STOS, OF CLEVELAND, OHIO, ASSIGNOR OF ONE-HALF TO JOHN KRAJEWSKI,
OF EAST CLEVELAND, OHIO.

CURTAIN AND SHADE SUPPORT.

Application filed June 30, 1928. Serial No. 119,540.

This invention relates to new and useful improvements in window fixtures and more particularly to an adjustable support for window shades and curtains and the primary 5 object of the invention is to provide a device of this character which when applied to the window frame will adjustably support both the window shade and the curtains or draperies.

10 A further object of the invention is to provide a window fixture which may be readily attached to or detached from a window frame without defacing the window frame. A still further object of the invention resides in providing means for effecting 15 an adjustment of the shade and curtain support both horizontally and vertically.

A still further object of the invention is to provide a device of the character described 20 which is simple and durable in construction, easily assembled and disassembled and which is well adapted for quantity production at comparatively low costs.

Further objects of the invention will appear as the description proceeds and by reference to the accompanying drawing in which Fig. 1 is a view in side elevation showing my improved support secured to a face 25 of a window frame; Fig. 2 is a view in front elevation on the line 2—2 of Fig. 1; Fig. 3 is a horizontal sectional view on the line 3—3 of Fig. 2; Fig. 4 is a horizontal sectional view on the line 4—4 of Fig. 2; Fig. 5 is a 30 vertical sectional view on the line 5—5 of Fig. 1; and Fig. 6 is a horizontal sectional view on the line 6—6 of Fig. 2.

In describing my invention, I shall refer to the drawing in which similar reference characters designate corresponding parts 35 throughout the several views and in which 1 indicates a portion of a window frame to which is secured a pair of adjustable clamping arms 2 and 3. The arm 2 has one end thereof bent inwardly as shown at 4 and 40 provided with teeth 5 and is also provided with a longitudinally extending slot 6, the central portion of the arm being bent into the form of a double loop 7, the purpose of which will hereinafter appear. Secured to

the opposite side of the arm 2 is a pin 8 50 having a head 9 and the adjacent end of the arm is provided with an inwardly directed projection 10. Connected with the arm and slidable with respect thereto is an arm 3 having a longitudinally extending slot 11 there- 55 in adapted to receive projection 10, and one end of this arm is provided with an outwardly directed projection 12 adapted to engage in slot 6 in the arm 2. The opposite end of the arm 2 is provided with an inwardly di- 60 rected portion 13 provided with teeth 14 and adapted to engage in the side face of the window frame. Slidably secured within the slot 11 is a screw 15 having a nut 15' on the inner end thereof and pivotally secured to 65 the screw 15 is a locking plate 16 provided with a cam slot 17 which is adapted to engage over the pin 8 on the arm 2. The arms 2 and 3 are fitted in position about the window frame as shown most clearly in Fig. 3 70 and the locking plate 16 is fastened over the pin 8 to hold the arms in place. Extending through the double loop 7 is a supporting member, indicated generally at 18, and comprising a pair of parallel extending arms 19 75 and 20 the outer ends of which are bent to form a loop 21. The loop 7 has an opening 22 therein into which fits an apertured plate 23. For securing the supporting member 18 in position with respect to clamping arms 2 80 and 3, I provide a thumb screw 24 which extends through slot 11 and projects through the opening in plate 23 and adjustably se- 85 cures the supporting member 18 to arms 2 and 3. Secured to the member 18 is a shade 90 supporting bracket 25 having therein a longitudinally extending slot 26 and an outwardly directed portion 27 having an aperture 28 therein adapted to receive one end of a shade roller 25'. For adjustably securing the member 25 to the support 18, I provide a member 29 shaped as shown most clearly in Fig. 4. The member 29 substantially surrounds each of the arms 19 and 20 and is ad- 95 justably secured thereto by means of a thumb screw 30. The thumb screw 30 also extends through the member 29 and through slot 26 in bracket 25 and serves to adjustably se-

cure the bracket 25 to the member 29. Also secured to the member 18 is a curtain bracket 31 which is looped as shown at 32 to receive curtain pole 32'. The curtain bracket 31 rests on the loop 21 and is slidably secured between the arms 19 and 20 of the supporting member 18. For adjustably securing the curtain bracket 31 to the member 18 I provide a member 33 which is rigidly secured to the curtain bracket 31 by means of a pin 34 and which may be clamped to the member 18 by means of a cam button 35. In order to provide for an adjustment of the horizontally disposed portion of the member 18 I provide a clamp 36 (see Fig. 6) which partially surrounds the arms 19 and 20 and which is secured to a foot piece 37 by means of a screw 38 and a cam button 39. The foot piece 37 bears against the face of the window frame 1. The cam button 39 may be turned 90 degrees from the position shown in Fig. 6 and the screw 38 turned to effect a proper leveling of the horizontal portion of the supporting member 18. The cam button is thus moved to the position shown in Fig. 6 to secure the parts in adjusted position.

In operation two of the above described devices are used for each window and are fitted in position by first adjusting the arms 2 and 3 to the width of the frame 1. The spurs or teeth 5 and 14 are driven into the edges of the frame. The locking plate 16 is then moved to the position shown in Figs. 2 and 3 and the screw 15 is tightened to secure the arms in holding position. The brackets 25 and 31 are then adjusted as to height by elevating or lowering the member 18 and securing the same in adjusted position by means of the thrust screw 24. The bracket 25 may also be adjusted horizontally to accommodate shades of different widths and secured in adjusted position by means of the thrust screw 30. The curtain supporting bracket 31 may be adjusted horizontally by sliding the same inwardly or outwardly as desired and secured in adjusted position by means of the cam button 35. The cam button 39 may be loosened and the screw 38 turned to adjust the position of the horizontally disposed portion of the member 18 as hereinbefore described.

It will now be clear that I have provided an adjustable support for window shades and curtains which will accomplish the objects of the invention as hereinbefore stated.

Having thus described my invention, what I claim is:

1. A device of the class described comprising a main supporting clamp adapted to be secured to the face of a window frame, a supporting member adjustably secured to said main supporting bracket, a shade support carried by said supporting member, a curtain supporting arm carried by said supporting member, means for adjusting the

position of said curtain supporting arm both horizontally and vertically and means for leveling said supporting member.

2. A device of the class described comprising a supporting clamp adapted to be secured to a window frame, means for locking said clamp to said window frame, a curtain supporting member carried by said supporting clamp and adjustable horizontally and vertically with respect thereto, and a shade support carried by said supporting arm and means for leveling said curtain supporting member.

3. A device of the class described comprising a single supporting member, a shade holder and a curtain support carried by said supporting member each being adjustable horizontally with respect thereto, means for securing said supporting member to a window frame, means for adjusting said supporting member vertically with respect to said securing means whereby to provide for both a horizontal and a vertical adjustment of said shade holder and curtain support.

4. In a device of the class described comprising a single supporting member having a vertical portion and a horizontally disposed portion, a shade holder and a curtain support carried by said supporting member, means for adjustably securing said supporting member to a window frame, means for leveling the horizontally disposed portion of said supporting member.

5. A device of the class described comprising a single supporting member having a vertically extending portion and a horizontally disposed portion, a shade support carried by said vertical portion and adjustable horizontally with respect thereto, a curtain support carried by said horizontal portion and adjustable horizontally with respect thereto, a clamp comprising a pair of adjustable arms adapted to be secured to the face of a window frame, said supporting member extending between said pair of arms, and means for adjusting the position of said supporting member with respect to said clamp and for securing the same in adjusted position whereby said shade support and curtain support are adjustable both horizontally and vertically with respect to the window frame.

6. A device of the class described comprising a supporting clamp adapted to be secured to a window frame, means for locking said clamp in securing position, a pair of parallel arms having horizontally disposed portions and vertically extending portions, a curtain supporting member supported by said horizontally disposed portions and adjustable horizontally with respect thereto, said parallel extending vertical portions of said arms being adjustably secured to said supporting clamp and adjustable vertically with respect thereto, and means for leveling

said horizontally disposed portions of said arms.

7. A device of the class described comprising a supporting clamp adapted to be secured to a window frame, a shade holder and a curtain support supported by said supporting clamp, each being adjustable both vertically and horizontally with respect to

said window frame, and means for simultaneously adjusting the vertical position of 25 said shade holder and curtain support after the supporting clamp has been secured to a window frame.

In testimony whereof, I hereunto affix my signature.

FRANK F. STOS.
